F. C. REUTTER

WIRE TWISTING TOOL

Filed Feb. 7, 1924

Patented June 23, 1925.

1,543,520

UNITED STATES PATENT OFFICE.

FRED C. REUTTER, OF LOS BANOS, CALIFORNIA, ASSIGNOR OF ONE-HALF TO MARK M. FINLAYSON, OF LOS BANOS, CALIFORNIA.

WIRE-TWISTING TOOL.

Application filed February 7, 1924. Serial No. 691,207.

To all whom it may concern:

Be it known that I, FRED C. REUTTER, a citizen of the United States, residing in the city of Los Banos, in Merced County 5 and State of California, have invented a new and useful Improvement in a Wire-Twisting Tool, of which the following is a specification.

My invention relates to improvements in 10 tools for twisting wires together as in the construction of concrete forms and the like.

The primary object of my invention is to provide an improved tool for twisting wires which will facilitate the engaging and 15 twisting of the wires and which may be manipulated conveniently within a restricted space.

Another object is to provide a device of 20 light but rugged construction which may be conveniently carried by a workman.

A further object is to provide a device of the character described embodying improved structure affording simplicity, and ease of operation.

25 I accomplish these and other objects by means of the device disclosed in the drawings forming a part of the present specification wherein like characters of reference are used to designate similar parts throughout said specification and drawings and in which:

Fig. 1 is a front elevation, partly broken away and shown in section, of my improved wire twisting tool;

30 Fig. 2 is a side elevation, partly in section, of the tool;

Fig. 3 is a section taken upon the line 3—3 of Fig. 1 in the direction indicated;

40 Fig. 4 is a broken front elevation showing the manner in which the tool is turned to twist the wires; and

Fig. 5 is a broken sectional view of a portion 45 of a concrete form showing the manner in which the tool is applied in twisting the tie wires thereof.

My invention is intended primarily for use in building construction for twisting together the wires by which vertical supports for concrete forms are tied together to prevent bulging of the form when the concrete is poured. In this connection it will be noted that the sides 1 of the form are supported by spaced upright supports 2 upon the outer sides of the form. Opposite 55 uprights are commonly tied together by

means of wires 3 carried around one of the uprights, crossed within the form, and then passed around the opposite upright the ends of each wire being twisted together upon the outside of the form. After the wires 3 60 are thus placed, the crossing strands of each wire are twisted together within the form to draw the uprights together to bring the sides 1 of the form firmly against temporary spacing members 4. Heretofore this twisting has commonly been accomplished by inserting a screw driver or other similar instrument between the strands of wire and turning said instrument about the wires. 65 To twist the wires together in this manner the instrument must be rotated entirely around for each twist imparted to the wire. The space between the walls of the form does not afford sufficient room to twist the wires conveniently in the manner, and furthermore the space is so obstructed by reinforcing bars 6 and the temporary spacing members 4 that usually the twisting can be accomplished only with considerable difficulty frequently resulting in injury to the 70 hands of the workman.

To overcome these objections I have devised an improved twisting tool which, by referring to the drawings will be seen to comprise a ratchet designated in general by the numeral 7, and consisting of an outer ring 8 and an inner ring 9 rotatably mounted within the outer ring. One of the rings, in the form shown in the drawings 75 the inner ring 9, is provided with a plurality of notches 11 arranged to be engaged by suitable pawls 12 secured within recesses 13 formed in the adjacent surface of the other ring, the notches and pawls being so arranged that when the outer ring 90 is rotated in one direction the pawls will engage the notches and cause the inner ring 95 to be rotated simultaneously in the same direction and to permit the free movement of the pawls past the notches when the outer 100 member is rotated in the opposite direction whereby said outer ring may be rotated independently of the inner ring.

The outer and inner rings 8 and 9 respectively are both split and the ends arranged in spaced relation to form gaps 14 adapted to admit the wires 3 when said gaps are moved to registering relation. Apertures 16 and 17 are formed in the outer 110 and inner rings 8 and 9 respectively to

receive a wire engaging member 18 slidably engaging said apertures and extending radially into the rings. The member 18 consists of a pin tapered at its inner end 5 and provided with a key 19 arranged to slidably engage a corresponding keyway 21 formed in the rings 8 and 9. The member 18 is also provided with a laterally extending pin 22 by which the member 18 may 10 be rotated relative to the rings 8 and 9. The pin 22 limits the outward movement of the member 18, and the key 19 is so positioned with respect to the pin 22 that when the member 18 is moved outwardly 15 to its extreme position the key will clear the outer edge of the outer ring so that the member may be turned by means of the pin 22 and the key moved out of alignment with the keyway thereby normally retaining the member 18 in its outer extreme position. When the member 18 is moved inwardly the tapered end extends diametrically across the inner ring 9, the outer end of the member 18 clearing the 20 inner surface of the outer ring 8 to permit the outer ring to be rotated independently of the inner ring. When moved to this position, the key 19 clears the inner edge of the keyway so that the member 18 may 25 be turned to move the key out of alignment with the keyway and thereby retain the member in the innermost or operative position.

30 The outer ring 8 is provided with a laterally disposed extension 23 recessed to receive the end of an actuating handle 24 held in engagement therewith by means of a set screw 25. The handle may be of any desired shape and size, or, if desired, a portion of some other tool carried by the workman, such as a screw driver or pair of pliers, may be inserted into the extension 23 and used for an actuating handle.

35 The rings 8 and 9 held in assembled relation by means of plates 26 and 27 screwed or otherwise secured upon the sides of the outer ring, the plates being shaped to match with the edges of the assembled rings.

40 In operation the ratchet is placed in engagement with the wires 3 to be twisted, the wires being admitted to the center of the ratchet through the gaps 14 in the rings. The member 18 is then moved from its outer position as shown in full lines in 45 Figs. 1 and 3 of the drawings, to the inner position shown in dotted lines, the tapered end of the pin being moved between the strands of the wire 3 and the pin 22 turned to the position shown in dotted lines in 50 Fig. 3 and in full lines in Fig. 4 to retain the member in its inner position as above explained. The outer ring 8 may now be rotated freely in one direction about the inner ring while a movement in the 55 opposite direction will cause the inner ring

and the member 18 to be turned about the wires 3. The tool is now operated as a ratchet in the ordinary manner by rotating the outer ring alternately in opposite directions to rotate the inner member in 60 one direction through successive partial rotations until the wire has been twisted to the desired amount as shown in Fig. 5 of the drawings. When the wires have been twisted the member 18 is turned by means of the pin 22 until the key 19 registers with the keyway and the member then moved to its outer position. The tapered end of the member 18 may be readily moved 65 out of engagement with the wire and the ratchet removed from the wire. By thus utilizing a ratchet action for twisting the wires, the tool may be operated in a very limited space as only a small portion of 70 rotation of the tool handle is necessary to effect any desired amount of twisting of the wire. As a clearance is always available for making at least a quarter turn of the handle the workman is thus enabled 75 to easily and quickly twist the wires without the usual inconvenience of avoiding reinforcing and spacing members and the frequent injury to the hands when such members are encountered.

Having thus described by invention what I claim as new and desire to secure by Letters Patent is,

1. A wire twisting tool comprising a ratchet; a wire engaging member slidably and rotatably mounted upon the ratchet and arranged to be moved to engage a pair of wires to be twisted together; means for holding the wire engaging member in operative or releasing position relative to the wires and ratchet; and means for actuating the ratchet and the wire engaging member to twist the wires. 100

2. A wire twisting tool comprising a ratchet; a wire engaging member slidably and rotatably mounted upon the ratchet and arranged to be moved between a pair of wires to be twisted together; a key secured upon the wire engaging member to slidably engage a keyway formed in the ratchet to 110 permit the member to be moved to and from operative position, said key clearing the keyway when the member is moved to either extreme to permit the member to be turned to move the key out of alignment with the keyway and thereby hold said member in either extreme position; and means for actuating the ratchet and the wire engaging member to twist the wires. 115

3. A wire twisting tool comprising a ratchet, and a wire engaging member slidably mounted upon the ratchet and arranged to be moved between a pair of wires to be twisted together, said ratchet consisting of an outer split ring the ends of which are slightly spaced, and an inner split ring ro- 120 125 130

tatably mounted within the outer ring, said rings having apertures adapted to slidably engage the wire engaging members; means connecting the outer and inner rings to cause the rings to be moved simultaneously in one direction and to permit the independent movement of the rings in the opposite direction; and means for actuating the ratchet and the wire engaging member to twist the 10 wires.

4. A wire twisting tool comprising a ratchet consisting of an outer split ring the ends of which are slightly spaced and having an aperture opposite the split ends, and 15 an inner split ring rotatably mounted within the outer ring, and having spaced ends and an aperture adapted to register with the ends and aperture of the inner ring, and means mounted in connection with the rings 20 to cause said rings to be moved simultaneously when rotated in one direction and to permit the rings to be rotated independently in the opposite direction; and a wire engaging member slidably mounted within 25 the apertures of the rings and extending radially into the rings, said member being adapted to be moved between a pair of wires introduced into the ring between the split ends of the rings and to extend across the 30 ring in operative position with the outer end of the member moved out of engagement with the outer ring to permit the outer ring to be actuated to rotate the inner ring and the wire engaging member and thereby twist 35 the wires together.

5. A wire twisting tool comprising a ratchet consisting of an outer split ring the ends of which are slightly spaced and having an aperture opposite the split ends, and 40 an inner split ring rotatably mounted within the outer ring, and having spaced ends and an aperture adapted to register with the ends and aperture of the inner ring, and means mounted in connection with the rings 45 to cause said rings to be moved simultaneously when rotated in one direction and to permit the rings to be rotated independently

in the opposite direction; and a wire engaging member slidably mounted within the apertures of the rings and extending radially into the rings, said member being adapted to be moved between a pair of wires introduced into the ring between the split ends of the rings and to extend across the ring in operative position with the outer end of the member moved out of engagement with the outer ring to permit the outer ring to be actuated to rotate the inner ring and the wire engaging member and thereby twist the 50 wires together, and means for holding the wire engaging member in operative position.

6. A wire twisting tool comprising a ratchet comprising inner and outer rings split upon one side to admit a pair of wires thereinto and having apertures arranged 65 opposite the split, and means mounted in connection with the rings to cause the rings to be moved simultaneously when rotated in one direction and to permit one of said rings to be rotated independently in the opposite 70 direction; a wire engaging member mounted within the apertures of the rings, and extending radially into the rings, the inner end of said member being normally spaced from the opposite side of the inner ring and the outer end of the member extending outwardly past the outer ring, said member being movable to an operative position between the wires and extending across the ring, the outer end of the member being moved inwardly out of engagement with the outer ring whereby said outer ring may be 75 rotated independently of the inner ring; a key secured upon the wire engaging member and movable past the ends of a keyway formed in the rings; and means for turning the member to move the key out of alignment with the keyway to engage either side of the ratchet whereby the wire engaging member may be held in either extreme position.

In witness whereof I hereunto set my signature.

FRED C. REUTTER.
